OIL BURNER SYSTEM COMPRISING A
VAPORIZING BLOCKTheophilus H. Smoot, Baltimore, Md., assignor to
Anchor Post Products, Inc., a corporation of
New Jersey

Application May 27, 1944, Serial No. 537,599

4 Claims. (Cl. 158—28)

1

This invention relates to a system of burning oil or other liquid fuel for heating purposes and involves the use of a heat-resistant capillary block with holes running through it to serve as a medium for the vapor entrainment of a liquid fuel. Such a liquid fuel is fed to the block, and air at relatively high velocity is forced through the holes to entrain the fuel in the form of a vapor which is either wet or dry. It is essential that some of the fuel be actually vaporized but I am using the phrase "entrained vapor" to cover the case where at least a part is vaporized while a part may be present in the form of minute droplets.

I realize that a great many attempts have been made to burn fuel with the aid of a heat-resistant capillary block but I believe that none of these devices has met with any permanent degree of success. By the present invention I aim to produce a burner which employs the capillary block principle in an efficient and commercial manner and this invention is based upon the discovery of what I believe to be the essential factors whereby such a device can be operated efficiently.

If a very low air velocity is used with the block, such as results from the use of natural draft, and relatively large holes are formed in the block, enough oil may be volatilized or entrained to support combustion, and this is particularly true if the block is exposed to the radiant heat of the flame. In such case, carbon is formed on the block but after the oil is burned off the flame will continue for quite a period of time and tend to burn off the carbon residues. With a device of this kind combustion is relatively slow but it has been suggested that the hot face of the block assists combustion by virtue of the so-called "surface combustion" effect.

When one attempts to increase the air flow in such a device by the use of forced draft there is an immediate loss of efficiency because the fuel (except perhaps in the case of an unusual fuel such as arctic gasoline) will not volatilize with sufficient rapidity. In fact, in such case a substantial increase in the air flow will extinguish the flame.

I have found that this difficulty can be overcome by carefully avoiding any "surface combustion" and by supplying heat to aid in volatilizing the fuel, which is supplied under specialized, controlled conditions. The most efficient way of supplying this heat is to preheat the air which is forced through the block.

Broadly speaking, my invention can be de-

scribed as an oil burner which includes a heat-resistant capillary block with holes running through it and to which liquid fuel is supplied from any convenient source so that it will be absorbed by the block. A fan or other equivalent means is employed for forcing air through the holes in the block and a mechanism such as a heat exchanger is employed for preheating the air which is forced through the holes.

10 When the air is heated to a temperature within the desired range (as later described), the liquid fuel will be vaporized or entrained with great efficiency, and a mixture of air and vaporized fuel will come out of the holes which is combustible but which is actually over-rich in fuel. To obtain the most efficient combustion, secondary air should be supplied, to be mixed with the primary air and vapor. This secondary air is also preferably heated, and it should be mixed with the primary air and vapor in such a way that entrained droplets will not strike the walls of the device until combustion has proceeded far enough substantially to prevent the deposition of carbon.

25 As regards the temperature to which the air should be preheated, this will depend in part upon the nature of the fuel. With a fuel such as ordinary motor gasoline, preheating cold outdoor air from zero or below to 100° F. will show 30 a marked benefit, though even with this type of fuel the temperature should preferably be above 150° F. With a heavier fuel such as kerosene or a #2 fuel oil such as is ordinarily employed with domestic oil burners, a higher temperature is 35 needed and this temperature preferably should not be below about 200° F. and certainly not below 190° F.

The principal care that must be taken is to see that the temperature does not go too high. 40 All of the hydrocarbon fuels usually employed in oil burners tend to start to decompose at a temperature in the order of about 400° F. and as a general rule this temperature should not be exceeded. In fact with the heavier fuels where the 45 ratio of carbon to hydrogen is higher than in the case of the lighter fuels, there is a tendency for carbon to be deposited at even lower temperatures and a preferred working range for the heated air with most of the liquid fuels used in this type of burner, will be found in the range between 190° F. and 330° F.

It is very simple to control the temperature of the porous block by controlling the temperature of the preheated air admitted to this block but 55 this can be done only if the construction of the

furnace is such that when the furnace is operating efficiently the block will not be heated above 400° F. by the direct furnace heat. To prevent this occurring I have found that certain structural points must be observed.

First of all, the porous block must not project into an actual combustion chamber. It is obvious that if it does, the temperature in the combustion chamber will be above 400° F. and the block will become too hot.

Even if the principal combustion takes place in a combustion chamber beyond the block, surface combustion should not be permitted to occur in or around the block. This can be prevented by providing a covering for the block largely enclosing such block except for the surfaces through which the air passages run. This prevents combustion taking place around the periphery of the block, and combustion within the block is prevented by forcing the air through the passages at a sufficient velocity so that flashback into the passages is prevented. It is advisable to provide a zone beyond the block, which may be termed the mixing zone, into which the air and volatilized fuel is discharged from the passages and to provide means for introducing into this zone secondary air at points removed from the face of the block. This mixing zone opens into a combustion chamber and by this arrangement the combustion against the face of the block is further prevented.

Actually I have found that the high velocity of the air forced through the passages in the block very largely reduces the static pressure on the walls of these passages and there is a tendency for the vapor to move toward the passages from those portions of the block which are subjected to normal static pressure. Even the exposed face of the block which is directed toward the flame will be subject to a static pressure approaching normal so that virtually no vapor will permeate this part of the block. As a result the block will stay clean even though its exposed face does reach a temperature higher than that at which one would expect carbon to be deposited. A capillary block of the type employed (which is ordinarily made of ceramic material) is an extremely poor heat conductor and excess heat will not penetrate far enough into the block to do any harm, but it is preferable to have the exits from the passages bellied-out so that the reduced pressure caused by the air velocity will not tend to draw vapor into those portions of the block around the outlet orifices. It is an interesting fact that my device can even be used as an efficient mechanism for burning gaseous fuels.

When a heavier fuel is used such that only a portion of it will be vaporized at the permissible temperature, the block will absorb the fuel in liquid form and may tend to operate wet. In such case, if the outlet face of the block is exposed to the direct radiant heat of the flame there is a substantial risk that carbon will tend to form on this face. When once carbon starts forming, the darkening of the face causes an increased absorption of radiant heat and the matter is progressive. Accordingly, I have found it advantageous when using the heavier fuels to supply a shield between the outlet face of the block and the flame, and to supply tubes running from the ends of the air passages through the shield. Such a shield may for example be made of a low density material such

as an insulation refractory, which may be supplied with metal-lined air and vapor passages.

Even though some of the heat (if properly controlled) may be supplied to the block by direct radiation, it is advisable to have the combustion air (and particularly the air used for entraining vapors) preheated to a temperature at least slightly higher than the average temperature of the block during operating conditions. Heat units must be supplied for vaporization, and if the air is colder than the block temperature, there will be a tendency for the air to cause condensation to take place either on the face of the passages or in the air stream, with the formation of fuel droplets which may not be properly consumed. The preheated combustion air maintains the entrained fuel in the form of a vapor in its travel from the place of entrainment to the place of combustion because of the available heat in the preheated combustion air as contrasted with entraining vapor in cold air. In the latter case, the vapor would give up heat to the air and there would consequently be a greater tendency for condensation to take place.

In view of this fact, I have found it desirable to keep the heating of the block by radiation down to a minimum and to rely upon the pre-heating of the air to supply the heat units for maintaining the block at the desired temperature and for supplying the additional heat units necessary for vaporization.

The combustion air may be preheated to the desired temperature either as a function of the design of the heat exchanger while passing all of the combustion air through it, or the heat exchanger may be designed to raise the temperature of a part of the combustion air above the desired point, and this air may be mixed with colder air to give the necessary temperature control. This last arrangement is particularly useful for quick starting under conditions of extreme cold, as the hot air alone can be used during the initial combustion and then as the block warms up, colder air can be blended in to give the desired temperature during operation.

When the burner is shut off, residual fuel will remain in the block for a short time. Accordingly, it is desirable to so arrange the device that the flow of air will continue for a time after the admission of fuel to the block has been stopped. This expedient is ordinarily sufficient when working with gasoline but when working with a heavy oil such as #2 furnace oil, the capillary block may be in a relatively wet condition when the fuel fed to the burner is stopped. In such case, the block will continue to produce vapors at a decreasing rate as the fire dies down. Finally a point is reached at which the vapors entrained in the air stream are not sufficient in amount to maintain a combustible mixture and the fire goes out. However, this will occur before all the vapors have been driven off and as the still warm air is passed through the block an odor may be produced at the exhaust. This can be stopped by providing mechanism so that at a predetermined time after the flow of fuel to the block is cut off, cold air is turned through the block which will rapidly reduce the volatilization of the fuel and extinguish the flame.

The block may be made of any desired type of heat-resistant material provided it has a capacity of absorbing the liquid fuel readily through capillary passages. Ordinarily it will be made of ceramic material. The holes through the block

may be located only in the upper part particularly if bottom feed is used, or may be distributed uniformly through the block where another arrangement for fuel introduction is used. These holes should be small enough so that the air passing through them will have sufficient velocity to prevent the flame from working back into the holes. For example, a burner of 100,000 B. t. u. per hour rated capacity will be large enough to heat an average well-built house of about 12 rooms. For such a burner the block can be a disk about 3 inches in diameter and about one-inch thick and the holes in the upper part can be about $\frac{1}{16}$ inches in diameter. In one case I employed 17 holes of this size. These figures are given only as an indication of desirable proportions and not in any way as a limitation.

Preheated air is forced through the holes by any convenient mechanism such as a fan, and a part of the preheated air will preferably pass around the outside of the block to serve as secondary combustion air. In order to prevent combustion from taking place adjacent the outer peripheral surfaces, which might lead to the block becoming too hot, the block is preferably encased in metal or other substantially impervious cover. If desired, a thin layer of air can be brought around the surface of the block, but in such case this layer should be caused to move at sufficient velocity to prevent the propagation of flame from reaching back around the sides of the block. If the block is subject to direct impingement of the flame, control is virtually impossible.

When using a volatile fuel such as gasoline I find it advisable to form the passages through the block in the upper part of the block and enclose the lower part of the block in a liquid-tight container. In such case the liquid fuel may be introduced into the block within this container and a safety device can be used so that the liquid fuel can never rise high enough to enter the fuel passages except as the fuel is absorbed and subsequently vaporized. With heavier types of fuel where vaporization is slower, this may lead to an unduly large absorption of fuel by the block and in such case it is sometimes advisable to feed the fuel into the top of the block but to control the amount of fuel admitted so that it is vaporized and consumed at the same rate it enters the block.

An igniter of proper design is used to initiate combustion when the device is first put into operation. With a light and volatile fuel I prefer to use a hot wire type of igniter, which may be located either inside or on the combustion face of the block. With a less volatile fuel satisfactory results can be had with a spark igniter.

A device utilizing the principles of this invention can be built very light in weight and relatively inexpensively, as it needs no moving parts except the fan for forcing the air through the heat exchanger and through the carbureting block, and in some cases, such as airplane and automatic heaters, this same fan can advantageously be employed for moving the air that is to transmit the heat to the point of application. It will also be found that one of the great merits of the device of this invention is its extraordinary range of modulation. It will operate efficiently for an unbelievably large variation in the amount of fuel consumed provided the supply of combustion air is adjusted proportionately.

In an ordinary oil burner unless the size of the nozzle is altered, a variation of 10% plus or minus in the amount of fuel consumed will usually be

the absolute maximum within the range of reasonable efficiency. With a structure made in accordance with my invention I have found that a given device can be operated over a range of from $\frac{1}{2}$ -pint of fuel up to 5 gallons of fuel per hour, which is an increase from minimum to maximum of 8000%. Of course if a burner capable of handling 5 gallons of fuel per hour is operated on the basis of only $\frac{1}{2}$ -pint per hour, the flame is not much more than a pilot light, but nevertheless such a light can be maintained with reasonably good combustion characteristics. Naturally if the amount of oil supplied to the burner is varied, the amount of air must also be varied but it is a very simple mechanical matter to control the supply of fuel and the supply of air by common mechanism so that they will be kept properly proportioned. In this way wide modulation in the amount of fuel consumed can be had without undue loss of efficiency.

The light weight with which the device can be built and the ability to modulate the amount of fuel consumed both are factors which make this device efficient for use as a heater to be employed in airplanes. With the larger planes it is desirable to have them warmed before the flight starts, but ordinarily much more heat is needed when a plane is subjected to heavy wind pressures at the intense cold of high altitudes as compared to that which is needed on the ground. My device readily lends itself to such a change and I have found that I can arrange to have this change made automatically. If the plane is to be heated before the flight, then while it is on the ground the air for both combustion and for convection heating may be supplied by a fan. This fan has its inlet connected to a pressure-ram or scoop. Under ground conditions when this fan is in operation the inlet to the fan will show a slight negative pressure relative to the surrounding air. When the plane is in flight the pressure-ram or scoop supplies more air than that drawn by the fan, and therefore pressure will be built up in the inlet, and pressure mechanism connected to this point can be employed automatically to turn off the fan and to operate a device for increasing the supply of fuel fed to the vaporizer. The increased quantity of air picked up by the pressure-ram then passes through the fan blades and through the rest of the device. Proper barometric controls may also be supplied in the combustion air line so that as the air rarefies at higher altitudes, the combustion air passage will open to maintain a controlled weight of air in the burner supply.

When operating the device as a fixed installation (as for heating buildings, ovens or the like) these particular controls will not be necessary but thermostatic or other mechanism can be employed to vary the amounts of air and fuel to be supplied to the burner as conditions may demand.

When light fuel is employed it is possible that the fuel will be actually vaporized. With heavier fuel part may be converted into vapor and also all or part of the fuel may be picked up from the surface of the holes through the block in the form of minute droplets. Even though these droplets are not theoretically vaporized nevertheless I am using the word "vaporized" as covering the conversion of the liquid into a gaseous form as illustrated by either type of operation.

This invention can readily be understood from the accompanying drawings which illustrate a form of device as embodied in a heater designed

for use in airplanes. In these drawings Fig. 1 is a sectional side view of the device; Fig. 2 is a view of the left hand end of the device as viewed in Fig. 1; Fig. 3 is a sectional detail through the capillary block showing the fuel feed and the igniter; Fig. 4 is a sectional plan view taken on the line 4-4 of Fig. 1; Fig. 5 is a vertical section through the absorbing unit and mixing chamber; Fig. 6 is a section on line 6-6 of Fig. 5; Fig. 7 is a section on line 7-7 of Fig. 1; Fig. 8 is an end view of the right hand end of the device as viewed in Fig. 1; Fig. 9 is a view of the outside of the device taken from the opposite side from that shown in Fig. 1; and Fig. 10 is a wiring diagram showing the operation of the controls of the mechanism.

These drawings were made from a burner of 90,000 B. t. u. per hour rated capacity which if utilized in an ordinary well-built house would be large enough to heat an average house of twelve rooms.

In the drawings the numeral 10 designates the porous refractory element and for this purpose a ceramic of high porosity is advisable. In order that the scale of the drawings may be appreciated this ceramic block in the device of the size specified was 3" in diameter. As here shown the block or element 10 is in the form of a section from a cylinder with a number of relatively small holes 12 passing through it in its upper half. This element is enclosed in a casing 14 which on one side covers the entire face except that holes are formed through it which register with the holes 12. On the other face as indicated in Fig. 6 there is a semi-circular opening which exposes all of the holes 12 and the face of the block between these holes. The pipe 16 inducts the fuel into the block 10 where it is absorbed. The pipe 16 is screwed tightly into the casing 14 so as to make a liquid tight joint in order that if any of the fuel delivered to the block 10 is not absorbed it will not run out into the device.

In order to provide a mixing chamber for the vaporized fuel and air a ring 17 is provided running out from the casing 14. In the periphery of the ring 17 are positioned vane-like members 18 which are slotted to admit secondary air to the point of combustion. An annular plate 20, which may be provided with a secondary plate 22, serves to provide an orifice through which the flame emerges.

The parts thus far described are supported in a cylindrical casing 24 by wing members 26 (see Figs. 5 and 6). The casing 24 forms the main combustion chamber and is provided with exterior fins as indicated at 28 in order that the heat generated in this combustion chamber may be readily absorbed by the convection air which passes around outside of it and is used to heat the plane.

As shown in Fig. 1 the products of combustion from the main combustion chamber within the casing 24 pass downwardly through the passage 30 which opens (as indicated in Fig. 7) into the off-center hole 32 formed in one end of the oval tube 34. The products of combustion return through tube 34 toward the combustion end of the machine and pass out through the pipe 36 to any desired type of vent or chimney (not shown). The oval tube 34 is also supplied with fins 37 to assist in heating the convection air.

Both the convection air and the combustion air are supplied by the blower 38 which is electrically driven when the plane is on the ground but is provided with vanes through which the air can

pass freely under flight conditions. This blower is shown in Fig. 1 without any air connection to the air inlet, but this connection is indicated in Fig. 2 by the numeral 39. This connection is intended to run to a source (ordinarily supplied as part of the ventilating system of large airplanes) which will carry air at slightly superatmospheric pressure when the plane is in flight.

It is intended that about twice as much air will be supplied during flight as when grounded.

The air for combustion is withdrawn from the central part of the blower 38 and passes upwardly through a pipe 40 and then over and down through the pipe 42 and runs toward the combustion end of the device through pipe 44 which runs longitudinally within the oval tube 34 (see Fig. 7). In this figure it is to be noted that the member marked as 44 is a tube running within the casing 34 whereas the ring indicated by the numeral 38 is not a tube passing through the casing 34 but is the opening for the combustion gas outlet which is shown more clearly in Fig. 1. The hot combustion gases pass through the tube 34 and the pipe 44 within this tube is exposed to the heat of the products of combustion and thereby this pipe and the combustion air is heated. In this device the parts are so designed that the air in the tube 44 is heated under normal operation to a temperature of approximately 300° F.

The heated air from the tube 44 passes upwardly through the passage 46 (see Figs. 1, 6 and 7) into the front end of the casing 24. Part of this air is then forced through the holes 12 while a part passes around the periphery of casing 14 to enter the mixing chamber through the vane-like members 18 to supply the necessary secondary air. It is to be noted that the casing 14 surrounds the outside periphery of the block 10 so that while this secondary air helps to heat the block, combustion around the periphery of the block is prevented.

Convection air from the blower 38 enters the outside casing 48 and is heated by the fins 28 and 37 as well as by the surfaces of the combustion chamber 24 and the oval tube 34, emerging through the passage 50 to be piped to the points where it is to be released and employed. Most of the parts of this device are made of sheet metal. It is understood that those parts which are to be exposed to high temperatures preferably are made of a heat-resistant chromium steel alloy.

The fuel feed is illustrated in Fig. 8. The fuel is introduced by a pipe 54 to a pump 56 (which may be of any desired type such as a gear pump or a bellows or diaphragm type of pump) driven through gearing indicated at 58 by a variable speed motor 60. From the pump 56 fuel passes through the tube 62 to a float valve 64 which is so arranged that it will close if the level of the fuel in the casing 14 rises high enough to wet the surfaces of the passages 12. Tube 66 runs from the pump 56 to a pressure switch 68 which will control the operation of the motor 60 if the pressure rises too high. Ordinarily the amount of fuel fed to the block 10 will be so proportioned to the combustion that it will be absorbed as soon as it reaches the block, so that no liquid will collect within the casing 14. In other words, the float valve 64 is purely a safety device and under normal conditions does not control the flow of the gasoline. This flow is controlled by the speed of the motor 60 and this is varied by a resistance in junction box 72 so that approximately twice as much fuel may be supplied to the block 10 when the plane

is in flight as is supplied to it when the plane is grounded. The member designated by the numeral 70 is a conduit for conducting electric current from the junction box 72 to the igniter. Member 73 is a static pressure tube to communicate the pressure of the combination air at the burner to the barometric control for combustion air.

The igniter here illustrated is positioned in the center of the block as shown in Fig. 3. This igniter has a casing 74 of conductive metal which is attached to the casing 14 by clip 76 and thereby is grounded. Within the casing 74 is an insulating mass 78 through which passes a screw 76 which is locked on the outside of the casing 74 by a nut 80 and an insulating washer 82. Brazed to the end of the screw 78 is a resistance wire 84 which is wound in a spiral about an electrical insulating support 86. The end of the resistance wire is connected to the casing 74 and thereby grounded as indicated at 88. One or more slots are cut in the face of casing 74 as indicated at 90 through which vapors can enter the casing 74 from the block 10.

When the ignition is turned on, wire 84 becomes hot thereby heating casing 74 which in turn heats the part of block 10 adjacent this casing vaporizing some of the absorbed fuel. The air passing through the passages 12 creates some suction at the outlet of the casing 74 and draws the warm vapors through the slots 90 into this casing where they are ignited. The flames from these vapors tend to ignite the vapors that are emerging from the passages 12 and gradually as the device heats up the block 10 becomes warmed to a temperature of approximately 300° F. at which point combustion reaches its maximum efficiency and the igniter can then be turned off. I have found that this operation usually takes in the order of about 3 minutes and therefore I preferably arrange to have the igniter remain on for about 5 minutes as will be explained hereafter.

With this device two timing operations are desirable. One controls the time that the igniter is maintained hot as has just been explained, and the other is the purging operation. When the heater is shut down the supply of fuel should first be shut off but the air should operate for an appreciable length of time afterward (say for example 15 minutes) in order to be sure that all of the absorbed fuel is cleared out of the block 10 while this block is still warm. These timing operations are controlled by a timing mechanism contained in a control box 92. This box can be located in any accessible place in the plane or mounted on the heater and is connected to the heater by the cable 94. Power is connected to this box by the conduit connection indicated at 96 and ordinarily this connection will be made at the main bus bar of the electrical system of the plane. Ordinarily this supplies current at a pressure of approximately 24 volts when the engines are not running and supplies the power directly from the generator at a pressure of about 28 volts during flight conditions. On the face of the control box 92 is a starting indicator 98 which is moved 120° in a clockwise direction when the device is started. A push button 100 is used for stopping the operation of the furnace. The particular construction of this control box is not part of my invention, but is made and offered for sale by others. Accordingly, its detailed construction is not shown. However the functional operation of this device will later be described in connection with the specific controls of my heater.

In addition to the pressure switch 68 to which reference has already been made and which is connected to the junction box 72 by the conduit 102 I supply a high temperature limit switch indicated at 104 which enters outside casing 48. This is normally a closed circuit switch but is controlled by a bi-metallic element so that it opens the circuit to turn off the heater if the temperature rises above a predetermined level.

The numeral 106 indicates a diaphragm which is operated by the air pressure in the air inlet pipe 39 which is connected to the blower 38. When the fan of this blower is operating, the pressure in the air inlet will be negative (sub-atmospheric) but when the plane is in flight and the usual ventilating system is working, a positive pressure will be developed in this air inlet and this pressure is conducted to the diaphragm switch 106 by a tube 108 to operate a throw-switch. At 110 is indicated a barometric control which supplies a butterfly valve in the pipe 42 so that as the plane rises and the air is rarefied, a controlled weight of air will be fed to the heater for combustion purposes. This is equal to about twice the weight of air supplied by the fan at sea-level.

The relationship of these controls and the timing of the mechanism is illustrated diagrammatically in Fig. 10.

30 When the indicator 98 (see Fig. 9) is turned its full limit of 120° in a clockwise direction, it winds a clockwork mechanism which controls the ignition connections and also the ultimate purging operation whereby the air current through the 35 ignition block is continued after the fuel is turned off.

In Fig. 10 the clockwork mechanism is represented by the wheel 112 and as this view is a diagrammatic view taken from the inside of the box, 40 this is wound by rotating it in an apparent counterclockwise direction and it rotates in an apparent clockwise direction when running. The shaft 114 rotates with the wheel 112 and this shaft also carries a cam wheel 116. A second 45 cam wheel 118 is mounted on a shaft 120 which is tensioned lightly for clockwise rotation by a spring 122. The shafts 114 and 120 are not connected together but nevertheless they are moved together with a permissible play of 30° by action 50 of the bar 124 which is fastened to the cam wheel 116 and enters a 30° slot in the cam wheel 118.

In Fig. 10 the parts are shown in their at rest position before the burner is started into operation. When the wheel 112 is rotated counterclockwise 120° the pin 126 rides up on the cam surface 128 closing the blower control switch 130. One arm of this switch is connected by the line 132 with a source of power here indicated as a generator 134 or alternatively a battery 136 as 60 has already been described. When the airplane is grounded power is supplied from batteries or an auxiliary power plant. In flight it is supplied direct from the engine generators. However, for the sake of convenience the drawings here indicate the power as being drawn from the generator. When the switch 130 is closed, power from the generator 134 passes through the line 132 and then through the line 138 to the ram switch 140. As it is presumed that the device will be started 65 while the plane is on the ground, the circuit through the ram switch is closed so that current flows to the blower 38 and thence to ground.

The final movement of the cam wheel 116 when rotating in the counterclockwise direction will 70 bring a pin 142 up onto the cam face 144. This

will close the ignition switch 146 so that current will flow from the line 188 through the switch 146 into the line 148. The current passes through solenoid 150 and thence through the line 152 to the igniter coil 84 and thence to ground.

When the solenoid 150 is thus energized, the switch 154 closes, supplying current to the line 156. In the meantime the cam wheel 118 has been rotated 120° so that the pin 158 just rides up on the cam surface 160 closing the switches 162 and 164. Current from the line 156 passes through the switch 164, the line 166 and thence to the solenoid 168 and through the manual stop switch 100 to the line 170. Thence it flows through the high temperature limit switch 172 (which is normally closed) to ground. When the cam wheel 118 is thus rotated 120° in the counter-clockwise direction, the armature 174 rotates with it and is held by the solenoid 168 so that cam wheel 118 is held stationary during the operating run.

Current from line 188 not only passes through the solenoid 168 but also through the line 176, through the resistance 178 and through the fuel pressure switch 68 to the variable speed motor 66 of the fuel pump 56, and thence to ground. Since this current is passed through the greater portion of the length of the resistance 178 the fuel pump will be operated at a relatively low speed. Thus when the device is supplied with air by the blower 38 the fuel supply is maintained relatively low.

After the device is operated about 5 minutes the igniter is disconnected. This is accompanied by the rotation of the cam wheel 118 through the arc of 30° permitted by the movement of pin 124 in the slot of the cam wheel 118. This 30° movement permits pin 142 to ride off of the cam face 144, opening switch 146 and thereby disconnecting the igniter 84. At the same time that switch 146 opens, switch 100 is closed so that current is supplied through the line 152 to the line 156 to compensate for the fact that switch 154 has been opened by the de-energizing of solenoid 150.

When the plane is in flight, air pressure will build up from the scoop in the inlet of the blower 38 and when this air pressure reaches a predetermined level it operates the ram switch 148 to disconnect the blower 38. At the same time, the switch throws over to close the circuit from the line 188 to a line 184 which passes through switch 162 and thence to line 186 which is tapped onto an intermediate point of resistance 178 so that a greater amount of current will reach the motor 66 and thereby increase the fuel flow to keep it in proper proportion to the increased flow of air that is entering from the air scoop. A fuel supply pilot light 188 (visible on the side of box 92) is also connected to line 186 as a safety measure. By-passing the resistance 178 is a circuit running through the pump exciter button 190. This can be used when the device is first turned on so that momentarily the pump will be operated at high speed to bring up enough fuel to saturate the block.

The fuel pressure switch 68 is so constructed that if the fuel pressure between float valve 84 and the fuel pump 56 rises too high, the fuel pressure switch 68 will open thereby cutting off the fuel pump until the pressure returns to normal.

In view of the fact that the battery 136 ordinarily supplies current at a lower voltage than generator 134, a battery switch 192 is supplied to by-pass a portion of resistance 178 when running on the batteries. As soon as the generators start operating this switch should be opened.

To shut off the burner, the manual stop switch 100 is opened (and the same effect will be had if the high temperature limit switch 172 should open). This will stop the flow of power through the solenoid 168 and release the armature 174 which will immediately permit pin 158 to drop off of cam surface 160, opening both switches 162 and 164 so that the fuel pump will be disconnected and stop operating. It will be noted that cam wheel 118 will still have a 90° angle to pass through before it comes to rest, which takes about 15 minutes, and it is only at the end of this period that pin 126 will drop off of cam face 128. During this time, the circuit will be maintained through switch 136 and lines 132 and 138 so that the blower 38 will remain in operation if the movement of the plane is not supplying sufficient air to keep open the ram switch that runs to the blower. This will insure a movement of air through the block 10 for an appreciable time after flow of fuel into this block is stopped and this will mean that all fuel that has been soaked up by the block will be driven out and burned so that the block will be left dry until it is desired again to start up the burner.

Incidentally I may point out that the device operates quite successfully when the casing or container which holds the capillary block (such as the casing designated by the numeral 14 in the example) is made with an enlarged opening on both sides of the block instead of having separate perforations to correspond with the air passages as shown in this specific example. I have also found that if the casing is sufficiently protected from the heat so that it does not rise to a temperature substantially above the temperature of the preheated air, the fuel can simply be fed into this casing and it is not necessary to feed it into the interior of the porous block as illustrated in the example.

When using burners of this general type in small sizes, as for heating automobiles or trucks, the action can be much more rapid than that which has been indicated above. For example, I have found that with the small type of burner the ignition cut-off can be taken care of by the use of a bi-metallic element so constructed that the ignition will cut off in about 30 seconds after the flame is initiated. Also with these small types of burners employing gasoline as a fuel, the purging can be accomplished in as short a time as one minute.

It is understood that the example given is intended only by way of illustration in order to explain the best mode in which I have contemplated applying the principles explained in the earlier part of my application and is not intended as a limitation, since the improvements and combinations which I claim to be my invention are set forth in the appended claims.

What I claim is:

1. In an oil burner, the combination of a heat-resistant porous block having air passages through it, means for delivering liquid fuel to be absorbed by such block, an enclosure for the block largely covering the surfaces of such block other than the surfaces through which the ends of such passage run to prevent fuel being volatilized and burned around and against the periphery of the block, means for forcing air through the passages in the block at a velocity adapted to prevent combustion within the block, means for forming a mixing zone into which such passages discharge vaporized fuel and air, means for admitting secondary air into such mixing

zone, means forming a combustion chamber in which the fuel mixture is burned, a heat exchanger communicating with the combustion chamber and including means whereby combustion air is preheated by the products of combustion, said air preheating means being so proportioned that when the furnace is operating efficiently such combustion air will be preheated to a temperature of at least 150° F., means forming a chamber on the inlet side of the block and means for admitting said preheated combustion air into such chamber at a temperature of between 150° F. and 400° F. to supply the heat units necessary for volatilizing fuel within said block.

2. A structure as specified in claim 1 in which the admitting means for the secondary air is constructed to admit air into the mixing zone at points removed from the face of the block.

3. A structure as specified in claim 1 in which the enclosure for the porous block includes a cup-like structure with the air passages above such cup-like structure and means is provided so that the liquid oil level will not rise above the upper edge of the cup-like structure.

4. The combination of a heat-resistant porous block having passages through it, an enclosure for the block largely covering the surface of the block other than the surfaces through which the ends of such passages run, a pipe to conduct oil to the block within such enclosure, a sleeve extending from the discharge end of the block to form a mixing zone into which such passages dis-

charge vaporized fuel and air, openings in such sleeve for admitting secondary air into the mixing zone, means forming a combustion chamber in which the final mixture is burned, means forming a header chamber on the inlet side of the block, a heat exchanger communicating with the combustion chamber and including a pipe running therethrough and opening into said header chamber for preheating air conducted to the burner, said pipe being so proportioned that the air passing through it will be heated to a temperature of between 150° F. and 400° F. to supply the heat units necessary for volatilizing fuel within said block and means including a fan for forcing air through said pipe and then through said block at a high enough velocity to prevent combustion within the block.

THEOPHILUS H. SMOOT.
